UNITED STATES PATENT OFFICE

HOWARD I. PIATT, OF LANSING, MICHIGAN, ASSIGNOR TO MOTOR WHEEL CORPORATION, OF LANSING, MICHIGAN, A CORPORATION OF MICHIGAN

SAFETY CUT-OUT FOR HEATERS

Application filed November 25, 1927. Serial No. 235,640.

In the operation of heaters, and particularly those operated by a gas-supplied burner, it not infrequently happens that when the gas supply is turned on, whether manually or automatically, no flame at the burner results by reason of the pilot flame having gone out. Thereafter, an attempt to light the burner results in a violent explosion in the gas-filled heating chamber. It is the primary object of my present invention to safeguard against such dangers, and to prevent waste of gas.

I accomplish this result by providing a dual thermostatic control of a valve or valves in the fuel line, one thermostat subject to the heat provided by the burner itself and another subject to the heat of the pilot; the latter constituting the dominant control.

A further feature of the invention is the provision against rapid cooling of the heater and heated water by cold air currents after the burner is extinguished. This is accomplished by a damper under control of a thermostat subject to the heat of the burner.

While the invention is exemplified in the following description and accompanying drawing by reference to a water heater supplied with gaseous fuel, it will be understood that the invention is not so limited in its application.

In the accompanying drawing,

Fig. 1 is a vertical section through a heater embodying the invention in its preferred form; and

Fig. 2 is a fragmentary sectional detail showing a modification.

In the drawing, the reference 11 designates generally a heating chamber communicating with a flue 12 centrally disposed within a boiler 13 containing a body of water 13^a. Within the heating chamber 11 is arranged a burner 14 supplied by the fuel line 15 from a gas source not shown.

Within an enlarged portion 16 of the fuel line is mounted a valve member 17 adapted to seat at 18 and carried by a valve stem 19. Upon the upper end of the valve stem is threaded a collar 20, the location of which axially of the valve stem is controlled through the rotation of the valve stem by a suitable

tool engaging within the kerf 21. A screw plug 22 gives access to the valve for adjustment. Extending laterally from the enlarged valve chamber 16 of the fuel line into the body of water within the boiler is a tubular housing 23, the interior of which communicates with the valve chamber and has mounted therein a bimetallic thermostatic bar 24. An arm 25 attached to and forming an extension of the thermostatic bar 24 engages between the two flanges of the collar 20 on the valve stem.

It will be understood that as the thermostatic bar 24 bends under temperature fluctuations of the body of water 13^a, the valve will be seated as the temperature rises and unseated as the temperature lowers.

Also extending laterally from the valve chamber 16 and in internal communication therewith is a tubular housing 26 having mounted therein a bimetallic thermostatic bar 27, the extension arm 28 of which normally lies above but out of contact with a collar 29 upon the valve stem.

A by-pass fuel line 30 leads from the interior of the housing 26 and supplies a pilot flame at 31.

The pilot 31 burns closely adjacent that end of the housing 26 within which is mounted the thermostatic bar 27, and the heat generated by the pilot flame preserves the thermostatic bar in such position that the extreme end of its extension arm 28 is out of contact with the collar 29. However, in the event the burner 14 and the pilot 31 are both extinguished, the cooling of the housing 26 will cause a deflection of the thermostatic bar 27 and the end of its extension arm 28 will bear upon the bar 29 and will force the valve 17 to its seat 18.

From the foregoing, it will be evident that so long as a flame is maintained at the pilot 31, the thermostat 24 will open and close the valve 17 to admit or to cut off fuel from the burner 14, maintaining the temperature of the water 14 within predetermined minimum and maximum limits of temperature. It will also be understood that if the pilot flame becomes extinguished for any reason when the burner is not in operation, a lowering of the

temperature of the water 13^a will be ineffective to open the valve 17 by reason of the fact that it is held closed by the stronger thermostat 27 which is no longer subject to heating by the pilot 31. Thus, in order to supply and ignite fuel at the burner 14, it is first necessary to light the pilot. Whereupon as the thermostat 27 becomes heated, the extension bar 28 is displaced from the collar 29 and the thermostat 24 is left free to open the valve 17. The opening of the valve 17 to supply fuel to the burner can only be accomplished when the pilot has burned a sufficient length of time to affect the thermostat 27.

15 While the invention is illustrated as embodying the two thermostats 24 and 27 acting upon the same valve 17, it will be clear that some measure of advantage incident to the invention will be attained by an arrangement of 20 two separate valves within the chamber 16, each acting upon its own seat and each controlled by one of the thermostats. However, the action of the two thermostats upon a single valve is advantageous in that the one valve is actuated every time the burner is turned on and off, thus precluding any sticking of the valve which might result if such valve were only actuated at the infrequent 25 intervals when the thermostat 27 is caused to function by the extinguishing of the pilot flame.

30 In Fig. 2, a slight modification is shown wherein the thermostat arm 28^a is moved longitudinally into and out of position above the collar 29 instead of laterally as in Fig. 1. Such arrangement effects a positive locking of the valve 17 in its closed position when the pilot is out, so that it cannot be moved by manual force supplementing the thermostat 24.

40 In order that heat may be conserved and rapid cooling of the heating chamber and boiler by cold air currents may be avoided when the burner is extinguished, a damper 32 is arranged in the heating chamber below the burner to control an air inlet or draft 45 33. This damper is actuated by means of a bimetallic thermostatic bar 34 which is subjected to the heat from the burner 13. When 50 the burner is in operation, the damper is permitted to occupy an open position as illustrated, but when the burner is extinguished, the cooling of the bar 34 closes the damper 32 by means of its engagement with the damper arm 35. The closing of the damper 55 precludes any draft of air through the heating chamber 11 and the flue 12. Upon the lighting of the burner, the resultant heat will cause the thermostat 34 to move to the 60 position shown, permitting the damper to open.

I claim:

1. A safety cut out for heaters comprising the combination with a fuel supply, and a 65 burner and a pilot both supplied thereby, of

a fuel line from the supply to the burner, a valve in said line, a thermostat connected with the valve and subject to heat generated by the burner and acting upon the valve to either open or close the same under variations of temperature, and a second thermostat subject to the heat of the pilot and also acting upon the valve in a closing direction, the second thermostat being adapted to overpower the first whereby the valve is held closed if the pilot be extinguished regardless of a lowering of the heat generated by the burner.

2. A safety cut out for heaters comprising the combination with a fuel supply, and a burner and a pilot both supplied thereby, of a fuel line from the supply having connections to both the burner and pilot, a valve in the connection to the burner, a thermostat continuously connected with the valve and subject to heat generated by the burner, said thermostat acting upon the valve to close the same at a maximum temperature and to open the same at a minimum temperature, and a second thermostat subject to failure to the heat of the pilot and also acting upon the valve in a closing direction at a minimum temperature, the second thermostat being arranged to overpower the first whereby the valve is held closed if the pilot be extinguished regardless of a lowering of the heat generated by the burner below a minimum.

3. A safety cut out for heaters comprising the combination with a fuel supply, and a burner and a pilot both supplied thereby, of a fuel line common to the burner and a pilot, a single valve in the fuel line to the burner only, a thermostat permanently connected with the valve and subject to heat generated by the burner, said thermostat acting upon said valve to close the same at a maximum temperature and to open the same at a minimum temperature, and a second thermostat subject to the heat of the pilot and also acting upon the same valve in a closing direction at a minimum temperature, said second thermostat being arranged to overpower the first whereby the valve is held closed to prevent the flow of fuel to the burner if the pilot be extinguished regardless of a lowering of the heat generated by the burner below a minimum.

4. In a safety cut-out for heaters, a fuel supply, a burner having connection with the fuel supply, a valve controlling the supply of fuel to the burner, a pilot burner connected with the fuel supply, a thermostat having a permanent operating connection with the valve and arranged to be influenced by the heat fluctuations caused by the operation of the burner to open and close the valve, a second thermostat and connection for closing said valve, the second thermostat being inoperative so long as the pilot

burner is ignited but of sufficient strength to overpower the first thermostat to hold the valve closed in case of failure of the pilot burner.

5. In combination with a heater having a fuel supply and main and pilot burners with separate connections to the supply, a valve in the connection to the main burner, a valve-actuating thermostat continuously connected
- 10 with the valve and responsive to heat fluctuations caused by the main burner to automatically open and close the valve, and a separate valve closing thermostat responsive to the failure of heat from the pilot burner
- 15 to overpower the first thermostat and close said valve and to hold the valve closed while the pilot is extinguished.

In testimony whereof I have hereunto subscribed my name.

20 HOWARD I. PIATT.
